UNITED STATES PATENT OFFICE.

NELSON Z. REOM, OF OAKLAND, CALIFORNIA, ASSIGNOR, BY MESNE ASSIGNMENTS, OF ONE-HALF TO COTTON BROS. & CO., OF SAME PLACE.

FIRE-LADDER APPARATUS.

SPECIFICATION forming part of Letters Patent No. 558,986, dated April 28, 1896.

Application filed March 29, 1895. Renewed January 31, 1896. Serial No. 577,635. (No model.)

To all whom it may concern:

Be it known that I, NELSON Z. REOM, a citizen of the United States, residing at Oakland, in the county of Alameda and State of California, have invented certain new and useful Improvements in Fire-Ladder Apparatus; and I do hereby declare the following to be a full, clear, and exact description of said invention, such as will enable others skilled in the art to which it most nearly appertains to make, use, and practice the same.

The present invention relates to a certain new and useful fire-ladder apparatus, and more especially to the manner of raising and lowering the ladders, whereby the same may be raised and adjusted to any given height, as will be hereinafter fully set forth in the drawings and described and pointed out in the specification.

20 The object of the invention is to provide a simple and effective mechanism for raising and lowering the ladders and for swinging the same from side to side in order that the ladders, after being extended to the required height, may be thrown against a building on either side of the street without changing the position of the apparatus.

In order to fully comprehend my invention, reference must be had to the accompanying sheets of drawings, wherein—

Figure 1 is a front side elevation of the apparatus, showing the ladders closed and lowered to a horizontal position. Fig. 2 is a top plan of the mechanism disclosed by Fig. 1. Fig. 3 is a rear side elevation of the mechanism set forth in Fig. 1, the ladders being broken away and the running-gear removed. Fig. 4 is a cross-sectional end view in elevation, taken on line $x-x$, Fig. 2. Fig. 5 is a 25 side view in elevation, showing the ladders and guide-supports extended. Fig. 6 is an end view of the mechanism illustrated in Fig. 5 viewed in the direction of the arrow. Fig. 7 is a detail cross-sectional view of the ladders when closed, taken on line $y-y$, Fig. 2; and Fig. 8 is a plan view showing the ladders extended.

In the drawings, the letter A is used to indicate the bed of an ordinary truck, and A' 30 the blocks secured thereto near the forward

end, which blocks are inclined from their center toward the outer ends. Upon these blocks rest and oscillate the bed-plate or block A², to the under face of which block is secured the transverse rod a, which rod rests 55 within bearings a' cut in the apex of the blocks A'.

To the oscillating plate A² is secured what I shall term the "supporting-frame" B, which frame projects upwardly from the oscillating plate for a short distance and is held in place by the supports B'. I also secure to the oscillating plate the base-block B², which block at one end is connected to the said plate A² by the hinge B³, Figs. 3, 5, and 6. The opposite end of this base-block is provided with a projecting stud b, which fits within the slot b' of the quadrant b², secured to the rear face of the frame B, Figs. 1 and 3.

In my apparatus I make employment of a 70 series of ladders, preferably four in number, C C' C² C³, Figs. 2 and 7. These ladders are connected one to the other, and in a full-size machine will be in length about twenty-five feet each, so that the ladders when extended 75 will form an extended ladder of about one hundred feet. The foot of the ladder C is securely fastened to the hinged block B², and to this ladder is secured the ladder C', the ladder C² being in turn secured to the ladder 80 C', and to the ladder C² is secured the ladder C³, as will be hereinafter described.

The lower end of the ladder C is firmly secured to the base-block B², hinged to the oscillating plate A². In the side faces of the 85 rails of this ladder I cut the groove or channel d, within which fit and slide the clamp-plates D, secured to and projecting inwardly from the lower end of the rails of the ladder C'. In the side faces of the rails of the ladder C', I cut the groove or channel d', within which fit and slide the clamp-plates D', projecting outwardly from the upper end of the rails of the ladder C. By means of these clamp-plates the ladder C' is firmly secured 90 to the ladder C. From the upper end of the side rails of the ladder C' outwardly project the clamp-plates D², which plates embrace the ladder C², the ends thereof fitting within the groove or channel d² cut within the face 95 100

of the side rails of the ladder C², while from the lower end of the side rails of said ladder inwardly project the clamp-plates D³, which embrace the side rails of the ladder C', the 5 ends thereof fitting within the channel or groove d' of the side rails of the said ladder C'. By means of the clamp-plates D² and D³ the ladder C² is secured firmly to the ladder C'. The ladder C³ is provided at its lower end with 10 the projecting clamp-plates D⁴, which plates embrace the side rails of the ladder C² and work within the groove or channel d² cut in the face of the side rails of said ladder as the ladder C³ is raised and lowered. From the 15 upper end of the side rails of the ladder C² project the clamp-plates D⁵, which plates embrace the side rails of the ladder C³, and the ends thereof fit within the groove or channel d³ cut in the face of the side rails of 20 the ladder C³. By means of the clamp-plates D⁴ and D⁵ the ladder C³ is firmly secured to the ladder C². It will thus be observed that the ladders when extended will be securely bound one to the other. These ladders are 25 extended vertically, successively, the ladder C³ being first extended, then the ladder C², and afterward the ladder C', all the ladders being preferably raised or extended through the medium of a single cable E, which cable 30 is run in the following manner: Within suitable bearing-boxes e, secured to the braces B', works the crank-shaft E', to which shaft I fasten the drums E² E³. One end of the cable is made fast to the drum E², and the 35 free end thereof is run upward over the pulley 1, secured near the top of one of the side rails of the ladder C, downward under the pulley 2, secured to the lower end of one of the side rails of the ladder C'; thence upward 40 over the pulley 3, secured near the top of the same side rail of the ladder C; thence downward under the pulley 4, secured near the bottom of one of the side rails of the ladder C², from whence it is run upward over the 45 pulley 5, secured near the top of the same side rail; thence downward under the pulley 6, secured near the bottom of one of the side rails of the ladder C³, after which the said cable is run across the ladder C³ and under 50 the pulley 7, secured to the lower end of the opposite side rail of said ladder. The cable is then run upward over the pulley 8, secured near the top of the side rail of the ladder C², opposite to pulley 5 and downward 55 under pulley 9, secured to the lower end of said side rail of ladder C² and upward over pulley 10, secured near the end of the side rail of ladder C', opposite to the pulley 3; thence downward under pulley 11, secured 60 to the lower end of the side rail of said ladder, and thence upward over the pulley 12, secured to the side rail of ladder C, opposite to pulley 1, and from this pulley the cable E is run downward and the free end thereof is 65 connected to the drum E³, as shown.

My object in using a single cable, which as

wound upon the drums E² E³ raises or extends the ladders, is that a uniform tension is maintained and there is no danger of the cable on one side becoming slack while that on the opposite side is taut. 70

Upon the crank-shaft E' is secured the ratchet-wheel F, which is engaged by the pawl F', pivoted to one of the brace-rods B'. By means of this pawl the ladders may be locked 75 and held at any desired height.

To the bed of the truck, transverse thereof, beneath the oscillating plate A², is secured the crank-shaft F', to which shaft the oscillating plate is connected by means of the short 80 cables or chains f f', Fig. 4. These cables or chains are so arranged as to wind upon the crank-shaft alternately. As the crank-shaft is turned so as to wind the chain or cable f, the opposite chain or cable is unwound. This 85 causes the plate A² to move downward as the cable or chain f is wound upon the crank-shaft and throw the extended ladder over to that side, while when the cable f' is wound upon the crank-shaft and the cable or chain 90 f unwound the extended ladder will be thrown in an opposite direction. In this manner the ladder is thrown to either side of the street without changing the position of the truck.

When the ladders are lowered and nested 95 together, they lie directly upon the bed of the truck, or in a horizontal position, and previous to the ladders being extended they are raised to a vertical position. This is accomplished through the medium of the cable H and the 100 guide-support. This support consists of a series of posts or standards so united as to permit of a vertical extension for a given distance. The post or standard H' is bolted, screwed, or otherwise secured to the forward 105 edge of the frame B. In the sides of this standard I cut the groove or channel h, within which groove or channel fits the end of the clamp-plates H², projecting from the lower end of the standard H³. The sides of this 110 standard or post have the groove or channel h' cut therein, within which groove or channel fits the end of the clamp-plates H⁴, projecting from the upper end of the standard or post H'. These clamp-plates hold the standard or 115 post H³ firmly secured to the standard or post H'. To the standard or post H³ is secured the standard or post H⁵, which is held in place by means of the clamp-plates H⁶ and H⁷, the former of which are secured to and project 120 from the lower end of the standard or post H⁵ and work or slide within the groove or channel h', while the clamp-plates H⁷ are secured to and project from the upper end of the standard or post H³ and fit within the 125 groove or channel h² cut in the sides of the post or standard H³. To the post or standard H⁵ is secured the post or standard I, by means of the clamp-plates I' I². The clamp-plates I' project from the lower end of the standard 130 or post I and fit within the grooves or channels h², while the clamp-plates I² project from

the upper end of the standard or post H⁵ and fit within the grooves or channels *i* cut in the sides of the post or standard I. The posts or standards which constitute the extendable 5 guide-support are secured one to the other in the same manner as the ladders.

The cable H, which raises or extends the guide-support, also raises the closed or nestled ladders from a horizontal to a vertical position. One end of this cable is secured near the upper end of one of the side rails of the ladder C, and the cable is run from this ladder over the pulley 13, secured near the upper end of the standard or post I, and under the pulley 14, secured near the lower end of said post or standard, and from this pulley is run upward and over the pulley 15, secured near the upper end of the post or standard H⁵, and is then run downward and under the pulley 16, secured near the lower end of the said standard or post, and from this pulley the cable is run upward and over the pulley 17, secured near the upper end of the standard or post H⁵, and thence downward under pulley 18, secured near the lower end of said standard or post, and from this pulley the cable is run upward over pulley 19, secured near the top of standard or post H⁵, and thence downward to the drum K, to which drum the free end is attached. This drum K is fastened to the crank-shaft K', which extends transverse of the truck-bed, near its forward end and works in bearings *k*. Upon this crank-shaft is also located the drum K². To this drum is fastened one end of the cable K³, which cable runs over a pulley K⁴, secured to the end piece of the truck-bed, and has its free end attached to the side rail of the ladder C opposite to the cable H. The drum K² is 40 loosely secured upon the crank-shaft K' and only rotates therewith when thrown into engagement with the cross-pin *k*¹² by the clutch *k*', Fig. 2.

The operation of my device is as follows: 45 As the crank-shaft K' is rotated, so as to wind the cable H upon the drum K, the guide-support is gradually extended until the posts or standards are raised their full height. As the cable is wound upon the drum K the closed or nestled ladders are gradually raised from a horizontal to a vertical position. When the guide-support has been extended its full distance, the closed ladders will extend in a vertical position. The ladders and guide-support are held in their position by throwing the pawl *k*² into engagement with the ratchet-wheel *k*³, secured to the crank-shaft, Fig. 2. As the cable H is wound upon the drum K the cable K³ is unwound from the loose drum K². After the ladders have been raised from a horizontal to a vertical position, as described, the ladders are then extended to any desired height by turning the crank-shaft E', so as to wind the cable E upon the drums E² E³.

In order to lower the extended ladders, it

is only necessary to release the pawl F', when the ladders will descend by gravity. To prevent the ladders descending too rapidly, I provide the friction-brake L, which, when thrown downward, Fig. 4, bears upon the periphery of the drum E³. After the ladders have been closed or nestled together they are lowered into a horizontal position by means of the cable K³ being wound upon the drum K². This drum is thrown first into engagement with the pin *k*¹². Then as the crank-shaft is rotated, so as to wind the cable K³ upon the drum K² with the rotation of the crank-shaft K', the cable H is gradually unwound from the drum K and the extension guide-support gradually lowered.

The ladders are lowered into a horizontal position by the base-block B² swinging over upon its hinged joint B³. As the base-block is swung over the pin *b* moves within the slot *b*' of the quadrant b².

While I have described and designated my invention as a fire-ladder apparatus, I do not wish to be understood as confining myself to such use, for I am aware that the invention may be used for other purposes—as, for instance, the erection of scaffolding for building. I am also aware that changes may be made in the arrangement of parts and details of construction herein shown and described without creating a departure from my invention.

Having thus described my invention, what I claim as new, and desire to secure protection in by Letters Patent, is—

1. In a fire-ladder apparatus, the combination with a series of slideable ladders lying normally in a horizontal position, of a vertical independent collapsible support arranged at one end of the horizontal position of the slideable ladders, mechanism for extending and permitting the collapse of the said support, connections between said support and the ladders whereby when the support is extended the ladders will be raised, means for extending the ladders, means for permitting the collapse of the ladders, and means for returning the ladders to a horizontal position.

2. In a fire-ladder apparatus, the combination with a series of slideable ladders, said ladders when not in use and closed designed to lie in a horizontal position, the extensible guide-support consisting of a series of slideable standards or posts, the clamp-plates for securing the standards or posts one to the other, a series of pulleys secured to the said posts or standards, a cable running over said pulleys, one end of said cable being secured to one of the ladders and the opposite end to a drum, and the crank-shaft for rotating said drum so as to wind the cable thereon in order to raise the extensible guide-support and throw the ladders from a horizontal into a vertical position.

3. In a fire-ladder apparatus, the combination with a series of slideable ladders, devices

for throwing the ladders from a horizontal to a vertical position, mechanism for raising and lowering the slideable ladders, a cable having one end connected to one of the ladders and 5 its free end to a drum loosely secured upon a crank-shaft, which cable when wound upon the drum draws the slideable ladders from a vertical position into a horizontal position, and a device for throwing the loose drum into

engagement with the crank-shaft so as to ro- 10 tate therewith and wind the cable thereon.

In testimony whereof I affix my signature in presence of two witnesses.

NELSON Z. REOM.
